ATTACHMENT FOR CHIMNEYS

Filed Feb. 23, 1929

Manley E. Gerry
INVENTOR.

UNITED STATES PATENT OFFICE

MANLEY E. GERRY, OF OAKLAND, MAINE

ATTACHMENT FOR CHIMNEYS

Application filed February 23, 1929. Serial No. 342,275.

This invention relates to chimneys and its general object is to provide an attachment for chimneys and flues that not only adds materially to the efficiency and proper function of the drafts, but prevents formation of deposits, such as creosote and other foreign matters on the inner wall of the flues.

A further object of the invention is to provide an attachment of the character set forth, that is simple in construction, inexpensive to manufacture and extremely efficient in operation and service.

This invention also consists in certain other features of construction and in the combination and arrangement of the several parts to be hereinafter fully described, illustrated in the accompanying drawings and specifically pointed out in the appended claims.

20 In describing my invention in detail, reference will be had to the accompanying drawings wherein like characters denote like or corresponding parts throughout the several views, and in which:

25 Figure 1 is a vertical sectional view illustrating the application of my device to a chimney.

Figure 2 is a fragmentary top plan view illustrating the adjustability of the collar which forms a part of my invention so as to provide a tight fit in chimneys.

30 Referring to the drawings in detail, the letter A indicates the chimney of the usual square cornered type and is shown for the purpose of illustrating the application of my attachment thereto.

The attachment includes an outer shell 1 which as shown is tubular in formation and tapers toward the upper end thereof whereby 35 the small end of the shell is disposed adjacent the upper end of the chimney.

40 Disposed within the outer shell 1 is what I term an inner shell 2 that is likewise tapered tubular in formation and tapered with the small end disposed uppermost. The outer shell has formed with its upper end a sleeve 3 that is tapered inwardly to an extent whereby the upper end of the sleeve 45 3 engages the upper end of the inner shell 2, while the lower end of the outer shell 1

is provided with a like sleeve indicated by the reference numeral 4 and the lower end of the sleeve 4 engages the lower end of the inner shell 2.

The connection between the sleeves 3 and 4 with the inner shell is such that a leak proof joint is formed, so as to provide a dead air space 5 between the shells. A cap is included in the attachment and this cap is of a size to fit the upper end of the chimney as shown in the drawing. The cap is made up of a plate 6 that rests upon the upper end of the chimney and formed with the outer edge of the plate is a continuous flange 7 that depends from said plate for 60 engagement with the outer side of the chimney. Formed with the inner edge of the plate 6 is a continuous lip 8 rising from the plate at an inclination and this lip 8 is secured to the sleeve 3 through the medium of 65 rivets 9 or other like securing means. Disposed between the plate 6 and the top of the chimney is suitable luting material in order to provide a leak proof connection between the plate and chimney as will be apparent, 70 and formed with the outer shell or secured thereto in any well known manner, is a partition that includes a plate 10 of a size to fit the chimney, and the plate 10 extends outwardly from the point of juncture of 75 the outer shell with the lower sleeve 4. The plate 10 has formed with its outer edge upturned flanges 11, and the corners of the plate 10 are cut-away as at 12. However, the space provided by cutting away the corners is filled by triangular shaped closure 80 members 13 that are provided with slots 14 to accommodate the shanks of headed pins 15 whereby the closure members are slidably mounted on the pins as will be apparent. 85 Each of the closure members have formed therewith upstanding flanges that are adapted to register with the upturned flanges 11 as shown in dotted lines in Figure 2. The closure members are held in operative position through the medium of a lug 16 that is pivotally secured to the plate 10 in an eccentric manner so that by rotating the lugs 16 they will slide the closure members 90 to their operative position. Each of the 100

lugs is provided with a finger piece 17 so as to facilitate the operation thereof as will be apparent. Suitable luting material may be disposed between the flanges 11, the flanges of the closure members 13, and the chimney, so that the space between the plate 10 and the cap may be sealed to provide a dead air space.

From the above description and disclosure of the drawings, it will be obvious that I have provided an attachment that protects the upper end of the chimney from the accumulation of deposits, such as creosote or other foreign matters, so as to promote the efficiency thereof, and the chimney is properly insulated where the attachment is arranged therein, to add to the efficiency of the drafts, as it will be apparent that the chimney will be retained in a warm condition for a maximum period of time due to the dead air spaces.

It is thought from the foregoing description that the advantages and novel features of my invention will be readily apparent.

I desire it to be understood that I may make changes in the construction and in the combination and arrangement of the several parts, provided that such changes fall within the scope of the appended claims.

I claim:

1. A chimney attachment comprising concentrically arranged tubular tapered shells, the innermost shell being longer than the outermost shell, sleeves connecting the ends of the shells in a manner to provide a dead air space between the same, said shells being adapted to be spaced inwardly from the inner side of a chimney, a cap having connection with the uppermost one of said sleeves and closing the space between the outermost sleeve and chimney, and a partition extending from the lower end of the outermost shell and having connection with the chimney in a manner to cooperate with the cap to provide a dead air space between the outermost shell and chimney.

2. A chimney attachment comprising an outer shell, an inner shell, said shells being tapered and tubular in formation, the inner shell being longer than the outer shell, tapered sleeves connecting the ends of said shells to provide a dead air space between said shells, said shells being adapted to be disposed in a chimney in spaced relation with the inner side thereof with their small ends disposed uppermost, a cap having connection with the sleeve at the upper end of said shells, a flange included in said cap and disposed about the outer side of the chimney, a partition extending from the outermost shell and cooperating with said cap to provide a dead air space between the outermost shell and chimney and means for adjusting the partition with respect to the chimney.

3. A chimney attachment comprising an

outer shell, an inner shell and being longer than the outer shell, said shells being disposed concentrically with respect to each other, and being of tapered tubular formation, tapered sleeves connecting the ends of said shells in a manner to provide a dead air space between the same, a cap including a plate, a lip formed with the inner edge of said plate and secured to the uppermost one of the sleeves, a flange formed with the plate and engaging the outer side of the chimney, a partition extending from the lower edge of the outer shell, flanges included in said partition and engageable with the chimney, closure members included in said partition and being slidably mounted to adjust the partition with respect to the chimney, means for securing the closure members in operative position, and said partition and cap having connection with the chimney in a manner to provide a dead air space between the outer shell and chimney.
